UNITED STATES PATENT OFFICE.

ISIDOR KITSEE, OF CINCINNATI, OHIO.

FIRE-ANNIHILATOR.

SPECIFICATION forming part of Letters Patent No. 257,595, dated May 9, 1882.

Application filed December 31, 1881. (No model.)

To all whom it may concern:

Be it known that I, ISIDOR KITSEE, a citizen of the United States, residing at Cincinnati, in the county of Hamilton and State of Ohio, have invented a new and useful Improvement in Fire-Annihilators, of which the following is a specification.

My invention relates to improvements in fire-annihilators in which several chemicals are held in separation and are discharged into a common reservoir, where they commingle and constitute a required fire-extinguishing gas or vapor.

My invention is an improvement on my applications for Letters Patent filed on or about the 7th and 25th of November and on or about the 12th of December, 1881.

Referring to the drawing which accompanies this application, and which is a vertical sectional view, A is a generating-reservoir. B is a tilting shelf. C are vessels having loose-fitting covers *ee*, adapted to contain chemicals in separation, resting on the tilting shelf B, which shelf is held in position by a cord, E. F is a pipe one end of which is connected with and opens into the generating-reservoir, and from thence extends through the several chambers of a building. This pipe has openings *f*, which openings are covered with easily-fusible caps G. Each of the fusible caps G retains in position a weight, H, fastened by a suitable mechanical device to a short cord, e, the other terminal end of the short cord e being fastened to a sliding ring, I. The pipe F is provided internally with sounding alarm-whistles K. The pipe F should have one or more of the openings *f*, with attached fusible caps G, and weights H in each chamber of a building.

The tilting shelf should be somewhat smaller in size than the interior of the generating-reservoir, so that it will readily turn therein, and said generator should preferably contain a given quantity of material, adapted to combine with the several chemicals contained in the vessels C, which, when brought in contact, form a required gas or vapor.

The generating-reservoir can be placed in any part of a building. I have found by experience, however, that the basement or lower story is the preferable location.

When, by the rise of temperature in any room supplied with my device, one of the fusible caps G is melted, the weight H is immediately released and falls downward outside 55 of the pipe F. The ring I can only slide upon the cord E a short distance, and the weight will forthwith withdraw a portion of the cord E through the openings *f* and cause the tilting shelf to turn and upset the vessels C and 60 discharge their contents into the reservoir, where the several chemicals will combine and constitute the required fire-extinguishing gas or vapor, which will immediately rise in the pipe F, and during its passage therein will 65 sound the alarm-whistles K. The generating vapor or gas will eventually escape through the apertures *f*, that have been opened by the melting of the fusible caps G.

Having now fully described my invention, 70 what I claim is—

1. In a fire-annihilator, a generating-reservoir having a tilting shelf held in position by a retaining-cord provided with independent branch cords, said branch cords having end 75 weights embedded within fusible substance, substantially as described.

2. In a fire-annihilator, a generating-reservoir having a tilting shelf supplied with vessels containing chemical reagents in separation, suspended by a cord having independent sliding branch cords, each of said branch cords having a terminal weight embedded within fusible substance, substantially as described. 80

3. In a fire-annihilating device, a conduit-pipe connected with and opening into a generator having openings sealed with fusible caps, as and for the purpose specified, substantially as described. 85

4. In a fire-annihilator, a conduit-pipe opening into and connected with a generating-reservoir, said conduit-pipe provided with interior sounding-whistles, substantially as described. 90

5. In a fire-annihilating device, a conduit-pipe connected with and opening into a generating-reservoir having openings sealed with fusible caps, said fusible caps retaining weights connected to a cord within said pipe, as and 100 for the purpose intended, substantially as described. 95

6. The combination, in a fire-annihilating device, of a generating-reservoir, A, provided with a tilting shelf, B, and vessels C, supplied with separate chemicals, adapted, when
5 brought into contact, to generate a fire-extinguishing gas, with a conduit-pipe, F, having openings f, closed with fusible seals G, which seals retain in position weights H, said pipe

F being further provided with internal sounding alarm-whistles, K, cord E, and branch 10 cords e, as and for the purpose intended, substantially as described.

ISIDOR KITSEE.
